UNITED STATES PATENT OFFICE.

CARL J. NYQUIST, OF LOS ANGELES, CALIFORNIA.

BURNER AND METHOD OF OVERCOMING FLAME PROPAGATION THEREIN.

1,248,895.

Specification of Letters Patent. Patented Dec. 4, 1917.

Application filed October 9, 1916. Serial No. 124,486.

To all whom it may concern:

Be it known that I, CARL J. NYQUIST, a citizen of the United States, residing at Los Angeles, in the county of Los Angeles and 5 State of California, have invented a new and useful Burner and Method of Overcoming Flame Propagation Therein, of which the following is a specification.

An object of this invention is to make 10 provision for overcoming the so-called flash-back or propagation of the flame in the burner toward the source of supply of the combustible gas employed in the device, thus minimizing danger in the use of the 15 burner and also avoiding injury to the burner caused by the flash-back.

Another object is to make provision for the utilization of the pressure of the ignited gases due to the flash-back to extinguish the 20 flame in the burner.

Other objects and advantages will appear in the subjoined detail description.

The accompanying drawings illustrate the invention.

25 Figure 1 is a side view of a burner embodying the invention.

Fig. 2 is a longitudinal mid section of said burner.

Fig. 3 is an enlarged sectional detail of 30 the intermediate portion of the burner.

Fig. 4 is a transverse section on line indicated by $\alpha^4-\alpha^4$, Fig. 3.

Fig. 5 is a transverse section on line indicated by $\alpha^6-\alpha^6$, Fig. 3.

35 Fig. 6 is a transverse section on line indicated by $\alpha^8-\alpha^8$, Fig. 3.

Fig. 7 is a side view of the primary mixing chamber.

It is well known that, in mixing a combustible gas and a combustion-supporting gas together such, for example, as acetylene and oxygen in a burner, varying pressures or other causes, possibly all of which are not known, tend to cause the flame or burning mixture to flash back through the burner and establish a flame at the inlet where the combustible gas discharges into the burner, thus producing intense heat adjacent said inlet. This flash-back occurs in gas stoves, 45 Bunsen burners and also in oxy-acetylene cutting and welding tools.

The flash-back in stoves and Bunsen burners is not especially detrimental to them, but in oxy-acetylene torches the heat of the flame

established by flash-back in the burner is sufficient to melt or ruin the parts of the torch adjacent the flame.

Efforts have been made to insure against flash-backs in oxy-acetylene torches by interposing foraminous disks or equivalent or 60 some suitable non-combustible filtering material between the gas inlets of the mixing chamber and the discharge end of the nozzle. It is obvious that foraminous disks or other flow-obstructing devices so placed greatly reduce the pressure so that much greater pressures are required to be maintained in the gas reservoirs or supply hose than is necessary where such foraminous disks or other 65 obstructions are omitted. The foraminous 70 disks, although they may be successful in preventing flame propagation in a burner with some gases, are unsuccessful where oxygen and acetylene gases are employed.

This device does not prevent the occurrence of flash-backs, but the construction is such that the force of some of the expanded gases due to the flash-back is exerted against the flame established by said flash-back so as to extinguish it immediately as soon as it occurs, thus preventing the parts adjacent the flame from becoming heated to such an extent as to destroy or ruin them.

In the drawings the invention is embodied in a torch adapted to use oxygen and acetylene gases, but it is understood that certain features of the invention are not limited to the torch shown or to the mixing and burning of only these gases.

There is provided a suitable mixing chamber 1 which may be substantially cylindrical as shown in the drawings or of other suitable form, said mixing chamber being provided at its rear end with a rearwardly expanding axial inlet 2 and near said inlet 95 with other gas inlets 3 that extend aslant forward and inward from the periphery of the mixing chamber to the interior thereof. The mixing chamber is surrounded between the gas inlets 3 and its outlet 4 with an annular flash-back chamber or pocket 5, there being an injector port 6 extending aslant inward and forward from the flash-back chamber into the mixing chamber so that the flash-back chamber communicates with 100 the mixing chamber.

The mixing chamber 1 has its forward end inserted in a socket 7, the inserted end being

of slightly less diameter than the diameter of the socket so as to leave a slight annular flash-back passage 8 between the mixing chamber and the wall of the socket 7. The 5 annular passage 8 is not absolutely essential to the effective operation of the burner but such construction is sometimes preferable. The socket 7 is formed in the rear end of a hollow stem indicated in general by the character 9, said stem having if desired a bend 10 near its outer end and said outer end being provided with a suitable nozzle 11 which is connected by screw-threads or otherwise to the stem. The bore of the stem 15 9 is contracted at 12 adjacent the socket 7 and is also contracted at 13 at its outer end adjacent the nozzle 11 and is expanded at 14 intermediate the contracted portions 12, 13, the contracted portion 12 being of greater 20 diameter than the bore of the mixing chamber 1. The portion 15 of the bore of the nozzle adjacent the stem 9 is expanded and is of larger diameter than the bore portion 13 of the stem and the tip portion 16 of the 25 nozzle bore is contracted.

The bore portions 12, 13, 14, 15, 16 in reality constitute an auxiliary mixing chamber as will be made clear hereinafter. The stem 9 is provided with a threaded portion 30 17 terminating at a shoulder 18, said portion 17 being screw-threaded into a cylindrical or other suitably shaped body forming a front head indicated in general by the character 19, and a portion of said cylindrical body forming the flash-back chamber 5.

The rear end of the mixing chamber 1 is screw-threaded at 20 into an axial passage 21 of the body 19 which is provided rearward of the flash-back chamber 5 with an 40 annular chamber 22 surrounding the mixing chamber adjacent the gas inlets 3.

Into the passage 21 is fastened by brazing or any suitable means or method a gas tube 23 and into the annular chamber 22 extends and is fastened a gas tube 24. The rear ends of the gas tubes 23, 24 are brazed or otherwise fastened into a rear head 25, there being ducts 26, 27 in said head communicating with the gas tubes 23, 24 respectively. 45 The head 25 is provided with valves 28, 29 which are connected to suitable sources of gas supply, not shown, said valve 28 controlling the supply of one of the gases, for instance oxygen, to the duct 26 and said valve 29 controlling the supply of another gas, for instance acetylene, to the duct 27.

Surrounding the tubes 23, 24 is a casing 30 which may be of cylindrical or other suitable shape and which is brazed or otherwise fastened at one end to the head 25 and at the other end to the body 19.

In practice, assuming that the valves 28, 29 are connected to suitable sources of gas supply, not shown, for example, oxygen and acetylene respectively, the operation of the

device is as follows: The workman using the torch, having first selected a nozzle and mixing chamber having the predetermined cross sectional area of bore for the size of the work to be operated on, will open the valves 70 28, 29 and will ignite the gaseous mixture issuing from the nozzle 11, and he will also adjust the gas pressures (in a manner well understood in the art) so as to obtain with this device evenly balanced pressures and 75 volumes of the gases, and he will hold the torch so as to direct the flame wherever desired. Gas flows through the tube 23, thence through the inlet 2 to the mixing chamber 1 and the other gas flows through the tube 24, 80 thence into the chamber 22 and thence through the inlets 3 into the mixing chamber. The gases issuing from the inlets 2 and 3 mix in the mixing chamber 1 and then expand into the bore portion 12 of the stem, 85 from whence the mixture flows into the bore portion 14, expanding therein. From the bore portion 14 the mixture flows into the bore portion 13, being accelerated therein, and then flows into the nozzle bore portion 90 15 which allows it to expand, thereby diminishing the velocity of its flow. Finally said mixture flows from the nozzle bore portion 15 through the reduced nozzle bore portion 16 where it is again accelerated, and the 95 mixture issuing from said bore portion 16 ignites to maintain the flame.

It is thus clear that as the mixture flows from the mixing chamber 1 to the tip of the nozzle 11 the flow of said mixture is alternatively accelerated and retarded, the retardation being effected by reason of the mixture being allowed to expand in the bore portion 14 of the stem and bore portion 15 of the nozzle, and the acceleration being due 100 to the contracted bore portions 13, 16; and that owing to the expansion and slowing up of the mixture, the gases constituting said mixture are more thoroughly homogenized.

It is understood that some of the mixture 110 in the mixing chamber 1 flows backward through the port 6 into the flash-back chamber 5 to form a pocket of explosive gaseous mixture so that, if for any reason the flame at the top of the nozzle flashes or strikes 115 back through the nozzle and stem bores into the mixing chamber, said flame will reach the flash-back chamber 5 before it reaches the gas inlets 2, 3, thus causing an explosion of the mixture in the flash-back chamber. 120 The force of said explosion drives some of the exploded gases through the port 6 into the mixing chamber and thence outward through said mixing chamber. The force of the expanded gases issuing from the port 6 125 into the bore of the mixing chamber is sufficiently great to produce a partial vacuum in that portion of the mixing chamber extending between the port 6 and inlets 2, 3, thus producing a suction sufficient to extinguish 130

any flame that may possibly have been propagated through the bore of the mixing chamber to the rear of the port 6 when the flash-back occurs.

- 5 When the explosion occurs in the flash-back chamber the burnt gases are expelled with great force through the port 6, making a partial vacuum in the flash-back chamber, and are directed outward by said port, which 10 in reality functions as an injector, so as to blow the flame outward away from the inlets 2, 3, thereby extinguishing the flame because of the absence of a combustible mixture to feed it, but immediately after the 15 flame is thus extinguished the combustible mixture quickly fills the mixing chamber and flash-back chamber as before and flows to the nozzle.

The flash-back and subsequent extinguishment of the flame of the flash-back occur in 20 an exceedingly small fraction of time so that the gaseous mixture issuing from the tip of the nozzle is readily ignited again by reason of the heat of the metal that is being worked 25 upon not having time to dissipate sufficiently to lower the temperature thereof below the degree necessary for ignition of said mixture.

It is understood that the annular passage 30 8 also fills with the mixture and that owing to the provision of said annular passage, when the flash-back occurs the flame may be propagated from the socket 7 through said annular passage to the flash-back chamber 35 5, and that some of the force of the subsequent explosion of the mixture in the flash-back chamber may expend itself outward through said annular passage. Of course owing to the mixing chamber being spaced 40 from the wall of the socket 7 said wall is more or less insulated against the conduction of heat from the mixing chamber.

From the foregoing it is clear that the invention not only comprises the construction 45 hereinbefore described but also comprises the method of overcoming flame propagation in burners by utilizing the propagated flame to explode a quantity of the gaseous mixture and then utilizing the force of the 50 expanded gases due to the explosion to blow out the propagated flame in the burner.

It is clear that the mechanical embodiment of the invention may be otherwise than shown and described and it is understood 55 that the invention is only limited by the spirit and scope of the appended claims.

The interior of the casing 30 which forms a handle for holding the device communicates with the atmosphere through an opening or openings 31 in the head 25.

The hereinbefore described specific construction of the chamber 22 and gas inlets 2, 3 and the described construction of the stem 9 and nozzle 11 is of advantage as an 60 aid in maximizing the effectiveness of the

torch when used with evenly balanced pressures. This enables lower pressures to be employed for work of a given size, and the advantage of using the lower pressures is that the metal being operated on will not be 70 blown away and disturbed by the welding flame as results where higher pressures are employed; also oxidation of the metal at the weld is minimized. The points of construction just noted above also conduce to 75 minimization in the consumption of the gases employed.

I claim:

1. The method of overcoming flame propagation in a conduit which consists in collecting an explosive charge, exploding said charge when a flash back occurs and directing the exploded gases into said conduit in a direction contrary to the direction of movement of the flash back, to blow out the flame. 80

2. The method of overcoming flame propagation in a conduit which consists in collecting an explosive charge near the entrance to said conduit, exploding said charge when a flash back occurs by the flash back 90 and directing the exploded gases into said conduit in a direction contrary to the direction of movement of flash back to blow out the flame.

3. A burner comprising a mixing chamber 95 having gas inlets and an outlet, and means whereby when flash-back occurs the force of the gases exploded by the flash-back will operate to blow out the flame in the burner.

4. A conduit at the end of which gas passed therethrough is burned, means for receiving explosive gas and of such volume as to produce an explosion when flash-back occurs, and means for directing said explosive gases toward said end whereby the 105 flame in the conduit will be blown out.

5. A burner comprising a mixing chamber having gas inlets and an outlet, a flash-back pocket communicating with the mixing 110 chamber, and a socket adjacent the outlet of the mixing chamber communicating with the flash-back pocket.

6. A conduit at the end of which gas passed therethrough is burned, said conduit having gas inlets, means located between said end and said inlets for collecting explosive gas to produce an explosion when flash back occurs, and means for directing said explosive gases toward said end, whereby the flame in the conduit will be blown out. 115

7. A burner comprising a mixing chamber having gas inlets and an outlet, a flash-back pocket communicating with the mixing 120 chamber, a socket adjacent the outlet of the mixing chamber communicating with the flash-back pocket, and a nozzle communicating with the socket.

8. A burner comprising a mixing cham- 125

- ber having gas inlets and an outlet, and a flash-back chamber, there being a port opening from the flash-back chamber into the mixing chamber and extending aslant inward and forward toward the outlet.
9. A burner comprising a mixing chamber having gas inlets and an outlet, a flash-back pocket, there being a port opening from the flash-back pocket into the mixing chamber and extending aslant inward and forward toward the outlet, and a socket adjacent the outlet communicating with the flash-back pocket.
10. A burner comprising a mixing chamber having gas inlets and an outlet, and means whereby to hold a gaseous mixture so that the explosion thereof by flash-back through the burner will operate to blow out the flame thus established in the burner.
11. A conduit at the end of which gas passed therethrough is burned, said conduit having gas inlets, a pocket, and a passage extending from said pocket into said conduit between said end and said inlets, and converging relative to the conduit in the direction of the flow of gases therethrough, said pocket being constructed and arranged to receive explosive gas and of such volume as to produce an explosion when flash back occurs.
12. A burner comprising a body having a passage and having a chamber and a pocket, and a mixing chamber having an axial bore and inserted in said passage, said mixing chamber having an inlet communicating with said passage and having an inlet communicating with the body chamber and having a port communicating with the pocket.
13. A burner comprising a mixing chamber having gas inlets and an outlet, a port opening into the mixing chamber, and a flash-back chamber communicating with said port and extending rearward thereof toward the gas inlets, the rearward extending portion of said flash-back chamber being closed.
14. A burner comprising a body having a flash-back pocket, a hollow stem having a socket at one end and fastened to the body, and a mixing chamber fastened to said body and projecting therefrom into said socket and provided with gas inlets and communicating with said socket and with the flash-back pocket.
15. A burner comprising a body having a flash-back pocket, a hollow stem having a socket at one end and fastened to the body, and a mixing chamber fastened to said body and projecting therefrom into said socket and spaced apart from the wall of the socket to leave an annular passage and provided with gas inlets and communicating with said socket and with the flash-back pocket.
16. A burner comprising a body having a flash-back pocket, a hollow stem having a socket at one end and fastened to the body, and a mixing chamber fastened to said body and projecting therefrom into said socket and provided with gas inlets and communicating with said socket and with the flash-back pocket.
17. A burner comprising a body having a flash-back pocket, a hollow stem having a socket at one end fastened to the body, and a mixing chamber fastened to said body and projecting therefrom into said socket and spaced apart from the wall of the socket to leave an annular passage and provided with gas inlets and communicating with said socket and with the flash-back pocket, said socket communicating with the flash-back pocket.
18. A burner comprising a flash-back pocket, and a mixing chamber extending through said flash-back pocket and provided with gas inlets and an outlet and provided between the outlet and the inlets with a port communicating with the flash-back pocket.
19. A burner comprising a body having a flash-back pocket, a hollow stem fastened to said body and extending into said pocket and provided with gas inlets, there being an annular space between the stem and mixing chamber communicating with the flash-back pocket.

Signed at Los Angeles, California, this 2nd day of October, 1916.
